UNITED STATES PATENT OFFICE

HENRY C. MILLER, OF MILWAUKEE, WISCONSIN; FIRST WISCONSIN TRUST COMPANY, OF MILWAUKEE, EXECUTOR OF HENRY C. MILLER, DECEASED, ASSIGNOR, BY MESNE ASSIGNMENTS, TO STATIONERS LOOSE LEAF CO., OF MILWAUKEE, WISCONSIN, A CORPORATION OF WISCONSIN

VISIBLE-RECORD SYSTEM

Application filed December 10, 1925. Serial No. 74,523.

This invention relates to a unit for holding the leaves in a visible record system.

Objects of this invention are to provide a unit having two systems of parallel members, 5 each of which carries impaling prongs adapted to receive the perforated leaves, and to so construct one of the parallel members that it may be shifted longitudinally with reference to the other member to thus bodily 10 shift one or a plurality of impaled leaves longitudinally of the unit without causing any separation of the parts.

Further objects are to provide means operable independently of the longitudinal shift- 15 able means to laterally shift the impaling prongs to permit the insertion or removal of a leaf.

Further objects are to provide an apparatus which will receive the leaves and permit 20 their free manipulation either singly or in groups to rock the leaves from one side to the other, and which is so constructed that it may be most easily operated for either of the motions described above, and which is 25 equipped with locking means adapted to lock the two leaf supports or prong-carrying members against relative displacement.

Further objects are to provide a device in 30 which there is no relative folding of the parts forming the unit, but in which each motion is distinct and may be independently secured with reference to the other motion, that is to say, in which the main parts of the apparatus may be moved laterally from each other with- 35 out longitudinal shifting or may be shifted longitudinally without lateral operation.

Embodiments of the invention are shown in the accompanying drawings, in which:—

Figure 1 is a view of the device showing it 40 in one position of adjustment.

Figure 2 is a transverse sectional view on the line 2—2 of Figure 1, such view being drawn to an enlarged scale.

Figure 3 is a view with the leaf rests re- 45 moved and showing the parallel bars in their closed position.

Figure 4 is a view corresponding to Figure 3 showing the parallel bars opened out.

Figure 5 is a sectional view on the line 50 5—5 of Figure 1.

Figure 6 is a view showing a further form of the invention and showing the parts in closed position.

Figure 7 is a view of this second form of structure showing the parts opened up. 55

Figure 8 is a longitudinal sectional view through one end of the structure shown in Figure 3.

Referring to the drawings, it will be seen that the unit consists of a base plate 1 upon 60 which the mechanism is mounted. This base plate is rigid and may be attached to any suitable support, if desired, or may be, as shown in the drawings, attached to covers 2, which are wholly independent of the unit 65 and may or may not be used as desired.

Upon the base plate of the unit, a pair of parallel bars 3 and 4 are mounted and are adapted to slide inwardly or outwardly bodily towards or from each other, as shown for 70 instance in Figures 3 and 4. These parallel bars are partially guided at their ends by means of flanges 5 and 6 turned up from the ends of the bed plate. However, positive means are provided for maintaining these 75 bars in parallel relation at all times. This means may comprise a pair of crossed levers 7 and 8, as shown most clearly in Figures 3 and 4 with one end of each lever pivotally attached to its appropriate parallel bar, as 80 for instance by means of the pivot pins 9 and 10. The other ends of the levers 7 and 8 are slotted, as indicated at 11 and 12, and the slots are so arranged that they cooperate with pins 13 and 14 carried by the parallel bars to 85 maintain the parallel relation of such bars as they are opened out.

In order to retain the parallel bars 3 and 4 in a floating relation to the base plate 1, and also in order to maintain such bars parallel to the center line of the base plate at all times, two pair of jointed levers, as indicated at 15 and 16, are provided and have their free ends pivotally attached to the crossed levers 7 and 8. Their jointed ends are provided with pins 17 and 18 which ride in suitable slots 19 formed in the bed plate 1. 90

A pair of leaf rests consisting of plates 20 and 21 are provided immediately above the parallel bars 3 and 4. The leaf rest 20 100

is rigidly secured by means of rivets to the bar 4 while the leaf rest 21 is provided with slots 22 which cooperate with headed studs 23 carried by the bar 3.

5 Each of the leaf rests 20 and 21 is provided with a manipulating knob or post, such as indicated at 24 and 25, respectively, in Figure 1. These knobs or posts slide in suitable cutouts formed in the guiding flange 6 of the base plate, as shown in Figure 1.

10 The leaf rests 20 and 21 rigidly carry a series of curved impaling prongs 26 and 27, respectively, spaced apart a distance equal to the spacing of adjacent perforations 29 in the leaves 28. These prongs, when the parts are in the position shown in Figure 1, together form parts of rings over which the leaves may be rocked.

15 Further, it is to be noted that the leaves 28 are provided with a series of spaced apertures 29 which are so arranged that they will engage either set of impaling prongs. As shown in Figure 1, the impaling prongs are arranged in pairs and are spaced apart the distance between adjacent perforations 29. However, when it is desired to alter the position of the leaves, it is merely necessary to slide the post 25 upwardly, as shown in Figure 1, thus sliding the leaf rest 21 in such direction, such leaf rest being shown as shorter than the leaf rest 20. This permits shifting of the relative position of the leaves carried by the two sets of impaling prongs and thus permits any longitudinal motion desired between the several leaves of the different sets of leaves.

20 Further, if it is desired to remove one of the leaves, it is merely necessary to manipulate the leaves to present such leaf in an accessible position uncovered by other leaves. Thereafter, the manipulating posts 24 and 25 are pulled apart, thus moving the parallel bars 3 and 4 apart and consequently moving the parallel leaf rests 20 and 21 apart. This 25 gives sufficient separation of the impaling prongs to permit the ready removal of the leaf. Obviously, a new leaf may be inserted in a similar manner.

25 It is to be noted that the points of the prongs are so shaped, as indicated in Figure 2, that the point of one prong lies horizontally opposite the outline of the body of the opposite prong. This facilitates the rocking of one leaf over from one set of prongs to the adjacent set of prongs without catching or tearing occurring at any stage in this operation.

30 In order to hold the leaf rest temporarily locked against relative motion, a latch 30 (see Figure 1) is pivoted to one of the leaf rests and is slotted and engages a stud carried by the other leaf rest, thus temporarily locking the parts against relative motion.

35 It is to be distinctly understood that this unit is provided with a rigid base plate and is

not intended for folding or rocking motion between the respective parts of the apparatus, nor is it intended for simultaneous shifting motion both laterally and longitudinally of one leaf rest with respect to the other. Instead, these motions are wholly independent and may be performed at will in any desired sequence, or in fact one of such motions alone may be had without necessitating the other movement.

70 It is to be distinctly understood that this unit may be attached wherever desired and is a complete unit in itself. Independent covers may be hinged to the base plate as separate entities, as shown, or else the unit may be attached to a desk or other support.

75 In the second form of invention illustrated in Figures 6 to 8, the base plate is indicated by the reference character 30 and is provided with a slot 31 within which the reduced portion 32 of a pin slides. This pin pivotally joins the small links 33 which have their outer ends connected to the lazy tong links 34. It is to be noted that the pin is provided with an enlarged portion 35 above the small links 33, as most clearly shown in Figure 8. Further, a second pin 36 is rigidly secured to the base plate 30 and projects upwardly therefrom. It is provided with an enlarged body portion 37 and with a reduced portion 38, such reduced portion fitting within a slot 39 of a longitudinally operable slide 40. This slide 40, it will be noted, is provided with a slot 41 which receives the upper end of the first-described pin and thus the slide 40 is guided and held against rocking motion. At its upper end the slide is provided with a rectangular notch 42 which receives the upturned lugs 43 of the leaf rests 44 when the leaf rests are in their innermost position, as shown in Figure 6. It is preferable to cut out the leaf rests 44 and the parallel bars 45, to provide opposed recesses 46 which receive or make room for the pins described above, when the parts are in their closed position. The construction of leaf rests and parallel bars are substantially the same as that described in detail for the first form of the invention.

80 It is to be noted that the lower flange 47 of the base plate 30 is provided with an outwardly projecting tongue 48 behind which the manipulating pin 49 of the left-hand leaf rest is adapted to slide. The other manipulating pin 50 of the right-hand leaf rest is received behind or below the tongue 51 of a slide 52, such slide being mounted upon the flange 47 and provided with a manipulating ear 53.

85 From this construction it is apparent that the parts may move either directly away from each other or that one of the leaf rests, for instance the right-hand one may be moved longitudinally without requiring opening of the device. Further, it is apparent from a

135

consideration of Figures 6 and 7 that two distinct locking means are provided. One slide 40 locks the leaf rests against rocking or outward motion, and the other slide 52 locks the movable leaf rest against longitudinal motion.

While special forms of locks have been shown and also particular forms of manipulating members for separating the leaf rests, it is to be distinctly understood that any type of lock may be employed as well as other types of manipulating members.

It will be seen that a novel form of unit has been provided in which the respective parts may be bodily separated while causing the impaling prongs to travel apart along straight lines directly away from each other. And further, it will be seen that one set of impaling posts may be shifted longitudinally of the unit without causing relative separation of the parallel bars.

It will be seen further that the apparatus may be most readily operated in a simple manner by mechanism constituting portions of the unitary structure itself.

Although the invention has been described in considerable detail, such description is intended as illustrative rather than limiting as the invention may be variously embodied and as the scope of such invention is to be determined as claimed.

I claim:

1. A unit for a record system comprising a pair of leaf rests lying in the same plane and each provided with impaling prongs, mechanism by which said leaf rests may be moved directly laterally apart and maintained in their initial plane, and an independent mounting allowing shifting of one of said leaf rests longitudinally of the unit, whereby two distinct relative motions of the leaf rest may be independently secured.

2. A unit for a record system comprising a rigid base plate, a pair of leaf rests mounted above said base plates, mechanism associated with said leaf rests and with said base plate by which said leaf rests may be moved directly laterally from each other while said leaf rests remain in the same plane, an independent mounting allowing the movement of one of said leaf rests longitudinally with respect to the other leaf rest, and a pair of impaling prongs carried by each of said leaf rests.

3. A unit for a record system comprising a rigid base plate, a pair of parallel bars mounted above said base plate, mechanism connecting said bars and base plate and insuring only parallel relative motion of said bars, a leaf rest carried by each of said bars, said leaf rests lying in the same plane, one of said leaf rests being rigidly secured to its parallel bar, and the other of said leaf rests being longitudinally slidably connected to the corresponding parallel bar, each of said

leaf rests having a series of impaling prongs.

4. A unit for a record system comprising a rigid base plate having guiding flanges at its ends, a pair of parallel bars positioned above said base plate and between said guiding flanges, mechanism connecting said base plate and said parallel bars and holding said bars in a parallelism and in the same plane while permitting their movement directly apart, a leaf rest carried by each of said bars, one of said leaf rests being movably secured to its corresponding parallel bar for sliding longitudinally of such bar, and a series of impaling prongs rigidly carried by each of said leaf rests.

5. A unit for a record system comprising a rigid base plate having guiding flanges at its ends, a pair of parallel bars positioned above said base plate and between said guiding flanges, mechanism connecting said base plate and said parallel bars and holding said bars in a parallelism and in the same plane while permitting their movement directly apart, a leaf rest carried by each of said bars, one of said leaf rests being movably secured to its corresponding parallel bar for sliding longitudinally of such bar, a series of impaling prongs rigidly carried by each of said leaf rests, and a pair of manipulating members secured to said leaf rests.

6. A unit for a record system comprising a rigid base plate having guiding flanges at its ends, a pair of parallel bars positioned above said base plate and between said guiding flanges, mechanism connecting said base plate and said parallel bars and holding said bars in a parallelism and in the same plane while permitting their movement directly apart, a leaf rest carried by each of said bars, one of said leaf rests being movably secured to its corresponding parallel bar for sliding longitudinally of such bar, a series of impaling prongs rigidly carried by each of said leaf rests, and locking means for temporarily holding said leaf rests against motion.

7. A unit for a record system comprising a rigid base plate, a pair of parallel bars positioned above said base plate, lazy tong mechanism connecting said parallel bars, and having a floating connection with said base plate, and maintaining said parallel bars in parallel relation while permitting their movement apart, a leaf rest rigidly secured to one of said parallel bars, a second leaf rest movably secured for sliding longitudinally upon the other of said parallel bars, a manipulating member secured to each leaf rest, and a series of impaling prongs secured to each of said leaf rests and adapted to receive perforated leaves.

8. A unit for a record system, comprising a pair of leaf rests lying in the same plane and each provided with impaling prongs, mechanism by which said leaf rests may be moved directly laterally apart and main-

tained in their initial plane, an independent mounting allowing shifting of one of said leaf rests longitudinally of the unit, whereby two distinct relative motions of the leaf rests may be independently secured, and means for locking the leaf rests against movement in either direction.

9. A unit for a record system, comprising a base plate, a bar adjacent each side of said base plate, curved impaling prongs carried by said bars with their ends so arranged that perforated loose leaves carried by the prongs of one bar may be slid thereover onto the prongs of the other bar, means guiding said bars upon the base plate for lateral separation, one of said bars being adapted also for longitudinal shifting movement relative to the other bar, and means for simultaneously locking said bars against separation and longitudinal shifting.

10. A unit for a record system, comprising a base plate, a pair of parallel bars in the same plane upon said base plate and each having a series of curved impaling prongs, the ends of the prongs being so arranged that perforated loose leaves carried by one series of prongs may be slid thereover onto the other series of prongs, parallel motion mechanism connecting said bars and said base plate, whereby said bars may be separated by a direct lateral movement, one of said bars being adapted for also being longitudinally shifted, latching means for simultaneously locking said bars against separation or relative lateral motion, and means for preventing longitudinal shifting of the longitudinally guided bar when said bars are moved towards each other and are unlocked.

In testimony that I claim the foregoing I do hereby set my hand at Milwaukee, in the county of Milwaukee and State of Wisconsin.

HENRY C. MILLER.
